UNITED STATES PATENT OFFICE.

LEWIS H. SLAGHT, GEORGE E. SUTTON, AND JOHN C. O'BRIEN, OF TORONTO, ONTARIO,
CANADA.

MANGLE.

1,193,623.

Specification of Letters Patent. Patented Aug. 8, 1916.

Application filed September 25, 1915. Serial No. 52,745.

To all whom it may concern:

Be it known that we, LEWIS H. SLAGHT, GEORGE E. SUTTON, and JOHN C. O'BRIEN, of the city of Toronto, in the county of 5 York, Province of Ontario, Canada, subjects of the King of Great Britain, have invented certain new and useful Improvements in Mangles, of which the following is a specification.

10 This invention relates to improvements on the mangle described in Lewis H. Slaght's United States Patent No. 883497 issued March 31st, 1908, and our object is to improve the construction of the mangle in certain 15 particulars.

In the original mangle it was found that the evaporated moisture from the goods could not escape quite freely enough during the passage of the goods back toward the 20 front end of the apparatus between the two sets of mangling apparatus. In the improved machine we have therefore so rearranged the aprons as to provide for the greatest freedom of escape of evaporated 25 moisture in both the ends and sides of the machine.

Some difficulties were experienced both in the feed to the upper set of mangling apparatus at the feed end of the apparatus and 30 the delivery to the lower set of mangling apparatus at the delivery end thereof, and improved feeding means form part of the present invention.

This present invention also relates to improved means for applying pressure to the 35 rollers which coöperate with the steam chests.

The invention is hereinafter specifically described and illustrated in the accompanying 40 drawings in which—

Figure 1 is a side elevation of the improved machine; Fig. 2 an elevation with one side of the frame removed; Fig. 3 a front elevation partly in section showing the 45 means for applying pressure to one end of one of the rollers; Fig. 4 a side view of some of the same parts; and Fig. 5 a plan view showing the means for delivering goods between a roller and steam chest at one 50 end of either of the sets of mangling apparatus.

In the drawings like numerals of reference indicate corresponding parts in the different figures.

1 is the frame of the machine suitably 55 shaped to support the different parts. On the frame are supported two sets of steam chests 2 with their coöperating rollers 3. Preferably there will be one roller and steam chest less in the lower set than in the upper, 60 so as to provide suitable space for the aprons carrying the goods as hereinafter described. The rollers may be driven in any suitable manner from the main shaft 4. Trains of 65 gearing for this purpose are indicated in dotted lines in Fig. 1 and need not be specifically described. The rollers have their journals 5 journaled in bearing boxes 6 which are vertically movable in guideways 7 in the frame. These boxes are each provided 70 with spring tensioning devices adapted to be simultaneously operated to simultaneously tension the rollers alike. These spring tensioning devices each comprise telescopic parts 8 and 9. The lower part 8 75 is formed on or secured to the box 6, (see Figs. 3 and 4). The lower part 8 is reduced in diameter as shown to provide a shoulder 10 against which bears a coil spring 11, the other end of which bears against the inner 80 side of the end of the part 9. The portion of the part 8 of reduced diameter passes through the end of the part 9 and has nuts 12 screwed thereon limiting the extension of the telescopic parts. On the part 9 are 85 formed one or more pairs of lugs 13—14 between which operate one or more eccentrics 15 carried by the shaft 16 suitably journaled on the frame. It is evident that by 90 rotating the shaft 16 that the parts 9 of the tensioning devices may be moved down as may be required to apply any desired tension to the boxes 6, the pressure, of course, being produced by the greater or less degree 95 of tension of the coil springs 11. When the eccentrics are rotated to throw up the parts 8, the springs extend until the upper ends of the parts 9 engage the nuts 12, when further movement of the eccentric results in lifting the parts 8 and the bearing boxes 6 100 to raise the rollers clear of the steam chests and finally sufficiently far to disengage their gears when the clothing is readily removed and replaced. The tensioning devices as constructed, it will be seen, cannot possibly 105 be tampered with after they are in position and the only means for varying their tension is by the rotation of the shaft 16.

A shaft 16 is provided at each end of each set of rollers. These shafts are operated by means of the following mechanism: A transverse shaft 17 is provided adjacent the feed end of the machine. This shaft, by means of bevel gearing 18 at each side, actuates the vertical shafts 19. Each shaft 16 is provided with a worm wheel 20 engaging a worm 21 on one of the shafts 19. The shaft 17 is provided with a wheel 22 by means of which it may be conveniently rotated. This wheel is preferably grooved to be engaged by an endless chain 23 which forms convenient means adjacent the operator's position for moving the same. The operator may thus conveniently change the tension to suit the requirements of the work on which the machine is operating.

In the machine shown in the prior patent hereinbefore referred to, a double feed apron was provided, one driven at the same rate of speed as the mangling rollers and the other at a considerably lower rate of speed. This arrangement was not found to be conducive to the most rapid work, and in the present machine we employ a single apron 24. This apron is suitably guided on rollers as usual, but is formed of a plurality of separate ribbons instead of being formed of a continuous belt fabric, (see Fig. 5). This apron is run at a certain speed, about 25% less than the surface speed of the roller which it feeds. As will be seen on reference to Fig. 1, the train of gears 25 which actuates the apron from the spindle 26 is designed to give less speed than the train of gears 27 which actuates the mangling roller. The formation of the apron 24 enables us to provide a plurality of fingers 28 which are secured to the roller 29 carrying the end of the apron nearest the mangling roller. These fingers reach forward into the opening of the space between the first roller and its coöperating steam chest, (see Fig. 2). The goods are thus guided right up to the point at which they are taken hold of by the roller and thus started on their course through the apparatus. The apron traveling at considerably less speed than the roller, the operator can more satisfactorily spread and straighten out the goods, and the goods once taken hold of by the roller are pulled rapidly away from the apron quickly giving the operator the space for placing the next article. The methods for supporting and tensioning the apron are not particularly novel and require no particular description.

An important feature of the invention lies in the arrangement of the aprons for carrying the goods back and forth through the apparatus where they are not subject to the action of the mangling rollers. In the old construction two aprons only were employed. In the present construction four are used, so arranged as to make the spaces

between the two sets of apparatus open at the ends as well as at the sides.

The first endless apron 30 is formed of continuous web and is carried on and guided by the rollers 31 suitably located so that the apron will take the goods as they pass out from between the last roller and steam chest of the upper series of mangling apparatus and carry the goods back to the feed end of the apparatus in contact with the under sides of the steam chest in the ordinary well known manner. This apron at the feed end of the apparatus brings the goods against the second apron 32 suitably carried on and guided by the rollers 33, which apron carries the goods back to the delivery end of the apparatus. It will be seen that the space between the aprons 30 and 32 is open at the delivery end of the apparatus. Preferably the aprons 30 and 32 are in contact for a short distance at the feed end of the apparatus to properly start the goods back on top of the second apron which is inclined downwardly toward the delivery end of the apparatus. The second apron delivers the goods to the third endless apron 34 which inclines downwardly toward the feed end of the apparatus and delivers the goods between the first roller and steam chest of the lower set of mangling apparatus. This apron is of the ribbon type like the apron 24 and is carried on and guided by the rollers 35. The roller 35 is located as close as possible to the opening between the first steam chest and roller of the second set of mangling apparatus, and is provided with the fingers 36 similar to the fingers 28 employed in connection with the apron 24. It will be seen that the space between this second apron and the lower set of mangling apparatus is entirely open at the feed end of the machine, giving free escape for the moisture evaporated. After traveling through the lower set of mangling apparatus, the goods are taken by the fourth apron 37 and are led back to the delivery end of the apparatus in contact with the under surface of the lower steam chest. This fourth apron is suitably guided on the rollers 38. Suitable tensioning devices 39 of ordinary type are provided in connection with one roller of each of the four aprons 30, 32, 34 and 37.

From the above description it will be seen that we have devised mangling apparatus which will effectively attain the objects of our invention as set out in the preamble to this specification.

What we claim as our invention is:—

1. In a mangle, the combination of a steam chest and a coöperating roller; an endless apron adapted to take goods from the roller and draw them back to the feed end of the apparatus against the underside of the steam chest; a second endless apron

adapted to receive the goods from the first mentioned apron and carry them back to the delivery end of the apparatus out of contact with the aforesaid steam chest; a 5 second steam chest and coöperating roller rotating in the reverse direction to the first; a third separate endless apron adapted to receive the goods from the second apron and deliver them to the second roller which 10 moves them toward the feed end of the machine; and a fourth separate endless apron adapted to take the goods from the roller and draw them back to the delivery end of the apparatus against the underside of the 15 second steam chest.

2. In a mangle, the combination of a steam chest and a coöperating roller; an endless apron adapted to take goods from the roller and draw them back to the feed 20 end of the apparatus against the underside of the steam chest; a second endless apron adapted to receive the goods from the first mentioned apron and carry them on a downward incline back to the delivery end of the 25 apparatus out of contact with the aforesaid steam chest; a second steam chest and coöperating roller rotating in the reverse direction to the first; a third separate endless apron downwardly inclined toward the feed 30 end of the apparatus and adapted to receive the goods from the second apron and deliver them to the second roller which moves them toward the feed end of the machine; and a fourth separate endless apron 35 adapted to take the goods from the roller and draw them back to the delivery end of the apparatus against the underside of the second steam chest.

3. In a mangle, the combination of a 40 steam chest and a coöperating roller; an endless apron adapted to take goods from the roller and draw them back to the feed end of the apparatus against the underside of the steam chest; a second endless apron 45 adapted to receive the goods from the first mentioned apron and carry them back to the delivery end of the apparatus out of contact with the aforesaid steam chest, the upper surface of the second apron being in 50 contact with the lower surface of the first apron for a short distance adjacent the feed end of the apparatus; a second steam chest and coöperating roller rotating in the reverse direction to the first; a third separate 55 endless apron adapted to receive the goods from the second apron and deliver them to the second roller which moves them toward the feed end of the machine; and a fourth separate endless apron adapted to take the 60 goods from the roller and draw them back

to the delivery end of the apparatus against the underside of the second steam chest.

4. In a mangle, the combination of a steam chest and a coöperating roller; a continuously moving apron adapted to feed 65 goods between the steam chest and roller, said apron being run at a lower surface speed than the roller coöperating with the steam chest, whereby goods on reaching the 70 roller are dragged over the surface of the feed apron and effectively straightened.

5. In a mangle, the combination of a plurality of ironing rollers; bearing boxes in which said rollers are journaled; guides in which said boxes are movable; a journaled 75 shaft adjacent each set of bearing boxes; pairs of eccentrics on said shaft one pair for each bearing box; and spring compressing devices engaging said boxes each provided with a leg at each side directly engageable by said pairs of eccentrics to vary the pressure on the rollers.

6. In a mangle, the combination of a plurality of ironing rollers; bearing boxes in which said rollers are journaled; guides in 85 which said boxes are movable; a journaled shaft adjacent each set of bearing boxes; eccentrics on said shaft one for each bearing box; and spring compressing devices engaging said boxes and directly engageable 90 by said eccentrics to vary the pressure on the rollers, each comprising two telescopic parts, a coil spring tending to separate them and a lug on one part engageable by the eccentric, the other part engaging a box. 95

7. In a mangle, the combination of a plurality of ironing rollers; bearing boxes in which said rollers are journaled; guides in which said boxes are movable; a journaled 100 shaft adjacent each set of bearing boxes; eccentrics on said shaft one for each bearing box; and spring compressing devices engaging said boxes and engageable by said eccentrics to vary the pressure on the rollers, each comprising two telescopic parts, a 105 coil spring tending to separate them, a lug on one part engageable by the eccentric, the other part connected with a box, a second lug engageable by the eccentric to lift the tensioning device, and means limiting the 110 extension of the telescopic parts.

Signed at Toronto, Canada, this 17th day of September, 1915, in the presence of the two undersigned witnesses.
